UNITED STATES PATENT OFFICE.

ARMIN H. WITTEMBERG, OF LOS ANGELES, CALIFORNIA.

DESIGN FOR A STOCKING.

Application filed July 25, 1928. Serial No. 27,582. Term of patent 14 years.

To all whom it may concern:

Be it known that I, ARMIN H. WITTEMBERG, a citizen of the United States, residing at Los Angeles, in the county of Los Angeles and State of California, have invented a new, original, and ornamental Design for Stocking, of which the following is a specification, reference being had to the accompanying drawing, forming a part thereof.

I claim:

The ornamental design for a stocking as shown.

ARMIN H. WITTEMBERG.
